UNITED STATES PATENT OFFICE.

SILAS M. FORD, OF ST. PAUL, MINNESOTA.

MACHINE FOR MAKING LATH BOARDS.

Application filed December 15, 1921. Serial No. 522,668.

To all whom it may concern:

Be it known that I, SILAS M. FORD, a citizen of the United States, and a resident of St. Paul, in the county of Ramsey and State 5 of Minnesota, have invented certain new and useful Improvements in Machines for Making Lath Boards, of which the following is a specification.

The main object of my invention is to provide positive means for bringing paper or other suitable material which has already been corrugated into more or less of a rectangular form into corrugations of a dovetailed shape.

Incidental objects are to provide means for gathering one corrugation at a time into a dovetailed shape, to provide means for keeping it in this shape, and during the process of passing the material through the machine form one of more of such dovetail shaped corrugations at a time until finally a sheet of material will emerge from the machine, with all of the corrugations, which may have been rectangular or irregularly 25 dovetailed shaped when the material entered the machine, in a symmetrical dovetailed shape formation.

With these and other incidental objects in view the invention consists of certain novel 30 features of construction and combination of parts, the essential elements of which are hereinafter described with reference to the drawings which accompany this specification.

In the drawings, Figure 1 is a plan view of the front end of my improved machine, and shows a fragment of a corrugated piece of impregnated paper about to be fed into the machine.

Figure 2 is a section taken on the line 2—2, Figure 1.

Figure 3 is a view similar to Figure 1, but of the rear end of the machine.

Figure 4 is a section taken on the line 45 4—4, Figure 1.

Figure 5 is a section taken on the line 5—5, Figure 3.

Figure 6 is a section taken on the line 6—6, Figure 5.

Figure 7 is a plan view of the front end of the machine with the upper forming and gathering means removed, showing merely the lower part of the machine.

Figure 8 is a similar view of the rear end of the machine.

Figure 9 is a conventional side elevation of the complete machine.

Figure 10 is an end view taken of the rear end of the machine showing the paper delivered in a dovetailed shape formation.

Figure 11 is an enlarged detail taken in plan view of one of the forming fingers, and Figure 12 is a side view of the same.

This machine is designed for making lath board similar to that shown in my Patent 1208535, December 12, 1916, "method of making lath boards," and the material as delivered by this machine can be used for passing the re-inforcing wires through the webs connecting the alternate lath like faces.

There have been many methods suggested for forming paper into dovetail shaped corrugations, and I have likewise devised numerous means for accomplishing this result.

However, when dealing with asphalt and impregnated felt products, the problem is extremely difficult on account of the enormous friction between the material and the means used in forming it.

For this reason I have found it advisable to first form the paper into a substantially rectangular corrugation and then take the central corrugation and form it into a dovetail shaped plait without disturbing the rest of the sheet. Then take the adjacent pair of corrugations and form them into dovetail shaped plaits and similarly draw each successive pair of rectangular corrugations into dovetail shaped plaits successively, rather than attempt to form all of the dovetail shaped plaits at one time.

As shown in Figure 9 the machine is built of a structural frame work and has two longitudinal angles, one at each side of the top of the frame work.

Mounted on the angles are a plurality of castings 9, each of which contains two bearings.

A set of upper shafts 2, 3, and a plurality of upper shafts 4 as shown in Figures 1, 3, 7, 8 and 9 are mounted in the upper bearings carried by the castings 9, and a second set of similar shafts 2', 3' and a plurality of shafts 4' are carried by the lower bearings of the castings 9.

A longitudinal power shaft 5, Figure 1,

adapted to be driven by any suitable means such as 6, drives the transverse shafts 2, 3 and 4 through the bevel gear pairs 7 and these shafts through the spur gear pairs 8 drive their co-operating shafts 2', 3' and 4' respectively.

The shafts 4 and 4' carry rollers 10 and 10' respectively, Figures 1, 3, 7, and 8.

A triangular shaped frame consisting of angles 11 and 12, Figure 1, is mounted above the upper set of rollers and from this frame is supported a plurality of T shaped guides 13 and 14. Transverse frame members 15 are supported by the upper triangular structure and these frame members carry a plurality of guide bars 16.

Likewise mounted on the triangular frame are transverse bars 17 which carry adjustment screws 18, Figures 11 and 12, provided for giving tilting adjustment of the forming fingers 19, which are mounted on the shafts 2, 3 and 4.

These forming fingers 19 are formed of sheet metal shaped as clearly shown in the drawing and mounted on the block 20.

Discs 21 are likewise supported from the blocks 20.

The shaft 2 carries a pressure collar 22 co-operating with a similar collar 22' directly below and mounted on the shaft 2'. The shaft 3 has a collar 23 thereon and the shaft 3' likewise has a collar 23'.

The first three shafts 4 each carry two collars 24, while the similar shafts 4' below each carry similar collars 24', these collars 24' being spaced between the collars 24 above.

The fourth one of the shafts 4 has two sets of forming fingers mounted thereon and likewise four collars and the next three of the shafts 4 likewise have four collars thereon, while the shafts 4' directly thereunder and co-operating with this set of upper shafts each carry 3 collars in staggered relation with the four collars above.

It will be noted from Figures 1, 3, 7, and 8 that the shafts are arranged in groups and that each successive group has two more sets of collars thereon.

When a sheet of impregnated paper such as that shown in Figure 2 is fed into the machine from the left, as shown in Figure 1, the central corrugation at 25 is gripped between the collars 22 and 22'.

If the corrugated sheet is fed directly into the machine the forming fingers 19 engage with the central corrugation at points 26, and force it into a dovetailed shape, the rest of the sheet not being affected.

As the paper is fed farther in, the T shaped guides 13 and 14 engage with the corrugations at 27 slightly drawing the paper between these points toward the center of the machine so the second set of forming fingers may engage with the cor-

rugations at 28 and 29, and thereby forcing these corrugations into a dovetailed shape.

The guide bars 16 ride in the corrugations to help align them as they travel from roller to roller and the collars on the various shafts likewise ride in these corrugations, the rollers 10 gently pressing the paper together and serving to move it forward through the machine.

The third set of forming fingers will engage the paper at 30 and so on through the machine, each set of guides 13 and 14 leading the proper pair of corrugations to the next sets of forming fingers, while the collars and guide bars keep the paper aligned and when the paper has finally passed through the machine, it emerges at the end in a dovetailed shape, as shown in Figure 10.

Where paper of a difficult nature is being handled it may be advantageous to take the paper as it comes from this machine and pass it to a similar machine that increases the amount of angle to the corrugation, or in other words makes a complete product of a lesser thickness.

This may also, with some classes of material, be done by passing the material as it comes from this machine through a pair of pressure rollers, or the paper may be used as is delivered from this machine.

Claims:

1. In a machine for making lath board the combination of means for positioning one corrugation of a sheet of corrugated material passing through the machine, means for changing the shape of said corrugation as it passes through the machine and means operating on said material after said first named means for changing the shape of a second corrugation of said sheet of material.

2. In a machine for making lath board adapted to have passed therethrough a sheet of corrugated material with the corrugation parallel to the longitudinal axis of the machine, the combination with means for locating one of the corrugations of said sheet of material, of means for changing the shape of said corrugation; simultaneously acting means for changing the shape of each corrugation next adjacent to said first named corrugation, and additional simultaneously acting means, functioning after said last named means, for changing the shape of the two corrugations adjacent to said last named pair of corrugations.

3. In a machine for making lath board the combination of means for passing a sheet of corrugated material through said machine with the corrugation thereof parallel to the longitudinal axis of the machine, of means for changing the shape of the central corrugation as it passes through the machine, a pair of individual means

- functioning after said first named means for changing the shape of the corrugations positioned one on either side of said central corrugation and means in the machine for 5 successively changing the shape of the two next adjacent corrugations of the material successively said machine having a sufficient number of said means for acting upon each of the corrugations of the sheet.
10. 4. In a machine for making lath board, the combination with a plurality of rollers for passing a sheet of corrugated material through the machine with the corrugations thereof running longitudinally of the machine, of a pair of forming fingers for acting on the central corrugation of the sheet, two pairs of forming fingers for acting on the two corrugations adjacent to the central corrugation of the sheet, and a plurality of 15 such pairs of forming fingers for successively acting upon each of the corrugations of said sheet.
15. 5. In a machine for making lath board the combination with means for passing a sheet of corrugated material through the machine with the corrugations thereof running longitudinally of the machine, of means for forming the central corrugation into a dovetail shaped plait, means spaced longitudinally from said first forming means for forming the two corrugations adjacent to the central corrugations into dovetail shaped plaits, and a plurality of such means spaced longitudinally of the machine for 20 successively forming a pair of corrugations 25 into dovetail shaped plaits.
20. 6. In a machine for making lath board the combination of a plurality of forming elements, the first of said forming elements being of such style that it will form a corrugation of a sheet of material into a dovetail shaped plait, and each of the remainder of said sets of forming elements being such that they will form a pair of corrugations 25 of material passed through the machine into dovetail shaped plaits, such sets acting successively as the material passes through the machine.
25. 7. In a machine for making lath board, the combination of a plurality of feeding rollers mounted transversely on the frame of the machine, means for driving said rollers, collars positioned on said rollers for riding in the depressions of the corrugations 30 of a sheet of corrugated material passing through the machine, forming fingers associated with said collars for forming a corrugation of material passing through the machine into dovetail shaped plaits.
30. 8. In a machine for making lath board, the combination of a plurality of feeding rollers mounted transversely on the frame of the machine, means for driving said rollers, collars positioned on said rollers for riding in the depressions of the corrugations 35 of a sheet of corrugated material passing through the machine, forming fingers associated with said collars for forming a corrugation of material passing through the machine into dovetail shaped plaits and 40 means for positively leading the corrugations to be formed to their proper forming means.
40. 9. In a machine for making lath board the combination with a plurality of feeding rollers, of means for driving said rollers, collars carried by said rollers and adapted to ride in the depressions of corrugations of material passed through the machine, forming fingers associated with said collars and 45 adapted to form the corrugations of the material into dovetail shaped plaits, guides for leading the corrugations to their individual forming means, and guide bars positioned to ride in the corrugations to keep 50 the material in alignment as it passes through the machine.
45. 10. In a machine for making lath board a forming finger positioned in the machine so as to engage with a corrugation of a sheet of corrugated paper fed through the machine and force said corrugation into a dovetail shaped formation.
50. 11. In a machine for making lath board a forming finger positioned in the machine so as to engage with a corrugation of a sheet of corrugated paper fed through the machine and force said corrugation into a dovetail shaped formation, and a disc positioned adjacent to said forming finger and adapted 55 to ride in the space between adjacent corrugations of the paper with the face of said disc parallel to the sheet of the paper.
55. 12. In a machine for making lath board the combination of a plurality of pairs of rollers adapted to pass corrugated material therebetween with the corrugation of the material passing longitudinally through the machine and transversely across the surface of the rollers, means associated with the upper rollers of the pairs for forcing the corrugations of material fed therethrough into dovetail shaped formation, said machine operating on the said corrugations successively as the material passes through the machine.
60. 13. The method of making lath board comprising the passing of a sheet of corrugated material through successive operations, the first of which changes the shape of the central corrugation, the next of which changes the shape of the pair of corrugations symmetrically positioned with respect to the central corrugation, the next of which changes the shape of the next pair of corrugations symmetrically positioned with respect to said central corrugation and continuously in the same manner until all of the corrugations of the sheet of material so acted upon have had the shapes thereof changed.

14. The method of making lath board comprising the successive operation on a sheet of corrugated material so as to first form the central corrugation thereof into a dovetail shaped plait, second form the pair of corrugations symmetrically positioned next to the central corrugation into a pair of dove tail shaped plaits, third form the next pair symmetrically positioned with respect to the central corrugation into dovetail ¹⁰ shaped plaits, and so on until all of the corrugations have been successively formed into dovetail shaped plaits.

SILAS M. FORD.
